UNITED STATES PATENT OFFICE.

EDWIN N. LIGHTFOOT, OF NEW YORK, N. Y., ASSIGNEE TO THE CUTLER-HAMMER MFG. CO., OF MILWAUKEE, WISCONSIN, A CORPORATION OF WISCONSIN.

ELECTRIC HEATER.

1,359,400.

Specification of Letters Patent. Patented Nov. 16, 1920.

Application filed June 22, 1920. Serial No. 390,920.

To all whom it may concern:

Be it known that I, EDWIN N. LIGHTFOOT, a citizen of the United States, residing at New York, in the county of Bronx 5 and State of New York, have invented new and useful Improvements in Electric Heaters, of which the following is a specification.

This invention relates to an electric 10 heater.

The heater to which this invention particularly applies comprises in general an elongated tubular jacket or casing, a terminal rigidly fastened to each end thereof, 15 a resistor arranged within the jacket and connected between the terminals, and insulation between the resistor and the jacket.

Among the objects of the invention is to provide a heater which is complete in itself, 20 which is efficient and durable, and which may be readily and economically manufactured.

Another object is to provide a heater which is bendable into different forms and 25 which, due to its inherent structure, will retain the form into which it is bent.

In accordance with this invention the resistor is helical or winding and the insulation is compacted and compressed thereon.

30 The jacket is ordinarily contracted cross-wise to thoroughly compress and compact the insulation.

The compressed and compacted insulation firmly holds the resistor in shape and 35 in place and insulates it from the jacket and its turns or convolutions from each other.

The helical or winding resistor may have 40 its turns or convolutions extensively varied in diameter and number per inch to vary throughout a wide range its ohmic resistance for a helix of given length or a given external heated surface.

The heater made in accordance with this 45 invention has the following advantages:—

It is complete in itself and may be employed alone or applied to sundry heating 50 appliances and associated therewith in various ways.

It is efficient and durable.

55 It may be readily, expeditiously and economically manufactured.

It may be bent into various forms to adapt it to the purpose for which it is to be employed.

Its insulation is so compacted that voids 55 and interstices are practically eliminated.

Its insulation is so compacted and compressed upon the resistor and around and about the same that the resistor and its convolutions are firmly kept in place and not 60 disturbed when the heater is bent into the required form.

It will retain the form in which it is made or bent.

Its terminals are firmly held in position 65 by the jacket and do not produce any strain upon the resistor.

Its jacket, insulation and resistor are not disturbed or strained by differential expansion and contraction thereof. 70

Its electrical and thermal characteristics are not changed when it is bent.

Its resistor may have a high ohmic resistance.

Its external heated surface may be small 75 for a high ohmic resistance.

Its resistor may have its ohmic resistance for a given external heated surface varied through a wide range.

Its length may be short for a resistor of 80 high ohmic resistance.

It has low thermal resistance and high thermal conductivity between the resistor and external heated surface.

It has a low temperature gradient from 85 the resistor to the external heated surface where the heat is delivered.

It may be operated at a high temperature.

It may deliver heat at a high rate and at 90 a low temperature.

The views in the accompanying drawings are as follows:

Figure 1 illustrates, partially in section, a heater provided with a plug terminal; 95

Fig. 2 is a sectional view on line 2—2 of Fig. 1;

Fig. 3 is a sectional view on line 3—3 of Fig. 1;

Fig. 4 is a sectional view on line 4—4 of 100 Fig. 1;

Fig. 5 illustrates, partially in section, a heater provided with a cap terminal;

Fig. 6 is a sectional view on line 6—6 of Fig. 5;

Fig. 7 is a sectional view on line 7—7 of Fig. 5;

Fig. 8 shows three resistors having widely

different lengths and ohmic resistances and formed into helices having the same length and diameter and different numbers of turns to adapt them to the same external 5 heater surface;

Fig. 9 shows in vertical section a pair of swaging hammers;

Fig. 10 is an end elevation of a pair of swaging hammers;

10 Fig. 11 is an elevation of a heater like that shown in Fig. 1;

Fig. 12 shows the heater bent into helical form;

15 Fig. 13 shows the heater bent into re-flexed form;

Fig. 14 shows a heater bent to form an immersion heater;

Fig. 15 shows the heater bent into looped form;

20 Fig. 16 shows the looped heater mounted upon the surface of a plate;

Fig. 17 is a sectional view on line 17—17 of Fig. 16;

25 Fig. 18 shows the looped heater arranged in the groove formed in a plate;

Fig. 19 is a sectional view on line 19—19 of Fig. 18;

Fig. 20 shows the looped heater embedded in a plate;

30 Fig. 21 is a sectional view on line 21—21 of Fig. 20;

Fig. 22 diagrammatically illustrates a filling machine by which the insulation is introduced into the jacket;

35 Fig. 23 is an enlarged vertical section through the spacing tamper for holding the resistor in place within the jacket and compacting the insulation therein; and

Fig. 24 is a cross-sectional view on line 40 24—24 of Fig. 23.

Heater.

Figs. 1 to 4 show a heater which is provided with plug terminals.

45 The heater comprises an elongated ductile tubular jacket or casing 1; plug terminals 2, one inserted in each end of the jacket and rigidly fastened thereto; a ductile helical resistor 3 arranged within the jacket and 50 connected to the terminals; and insulation 4 compacted within the jacket and around and about the resistor.

Figs. 5 to 7 show a similar heater provided with cap terminals instead of plug 55 terminals.

The insulation is compacted when it is first put into the jacket, and then after the terminals are secured in position, the jacket is ordinarily contracted crosswise to 60 further compress and compact the insulation.

The dimensions which obtain in a heater for general purposes are as follows:

Jacket:

65 Length about thirty (30) inches.

Outside diameter about one-quarter (1/4) inch (before contraction about five-sixteenths (5/16) inch.

Inside diameter about three-sixteenths (3/16) inch.

Helical resistor:

Outside diameter of helix three-thirty-seconds (3/32) inch.

Diameter of resistor wire from about one-one hundred twenty-fifth (1/125) inch to 75 about one-fortieth (1/40) inch.

Number of turns per inch from about eight (8) to about one hundred (100).

These dimensions may be varied according to the purpose for which the heater is 80 employed.

Jacket.

The jacket 1 is made from a ductile straight tube of any suitable material, for instance, iron, steel, copper, brass, nickel-chromium, 85 nickel-copper or nickel-iron.

A copper jacket is particularly suitable where the heater is to be immersed in water or other liquid or is to be bent on a short 90 radius.

After the heater has been assembled and the terminals permanently fastened in place, the jacket is swaged or otherwise contracted crosswise to reduce its diameter and thereby tightly compress the insulation upon and 95 around and about the resistor.

The crosswise contraction of the jacket and the resultant compression of the insulation upon the resistor tends to increase the cross section of the resistor and decrease its 1 ohmic resistance, and not to decrease its cross section and increase its ohmic resistance.

Further the jacket is not materially elongated or increased in length.

Figs. 9 and 10 show a pair of swaging hammers by means of which the jacket may be hammered or swaged to contract it. These hammers are placed in a machine by 1 which they are rapidly vibrated and while they are vibrating the heater is moved back and forth and turned between the same until the jacket has been reduced in diameter throughout its length.

Resistor.

The resistor is made from any suitable ductile material, for instance, nickel-chromium, nickel-steel, nickel-copper or other resistance wire.

The number of turns per inch in the helix depends upon the lengths of wire and ohmic resistance to be obtained.

In order to facilitate making the resistor, the helix may first be wound with its turns close together and then stretched out to obtain the number of turns per inch necessary to give the required ohmic resistance.

Fig. 8 shows three helical resistors made from wire of the ~~same~~ size and material.

These helices are different only in the number of turns per inch. Inasmuch as the number of turns per inch vary materially, the length of the wire and consequently the 5 ohmic resistance is widely varied.

Among the advantages which come from the helical resistor is that it gives a relatively high ohmic resistance for a helix of a given length and diameter and a given 10 external heater surface, which ohmic resistance may be varied through a wide range by simply varying the number of turns per inch or the diameter of the turns or convolutions or both.

15 The resistor is provided at each end with a connector 5 by means of which it may be connected to the terminals.

This connector is of greater cross section than the resistor so that it will not become 20 overheated.

It may be formed by straightening the end of the wire, folding it upon itself several times, and then twisting the strands together. Of course, the connector may take 25 other forms and be made in different ways.

Terminals.

The plug terminal 2 (Fig. 1) has a plug 30 which is inserted into the jacket and insulated therefrom by an insulating sleeve 7.

The jacket is swaged or otherwise contracted upon the plug so as to firmly bind the terminal in place.

35 The plug may be provided with an annular groove to allow an indentation to be made in the insulating sleeve and the jacket to assist in fastening the terminal to the jacket.

40 An insulating bushing 8 formed to cover the jacket may be threaded upon the plug. This bushing protects the insulating sleeve and further insulates the plug from the jacket.

45 The terminal is provided with a central hole which receives the connector 5 and has an indentation 9 swaged or otherwise formed therein to bind the connector thereto.

The cap terminal (Fig. 5) has a cap 10 50 which receives the jacket and is insulated therefrom by an insulating sleeve 11. The cap is swaged or otherwise contracted upon the jacket to fasten it in position.

Insulation.

55 The insulation may be made of various materials and inserted in different ways. Among the insulating materials which may be employed are magnesium oxid, quartz, 60 soapstone or talc. Granular magnesium oxid is particularly suitable as it may be readily inserted and compacted and compressed. Of course, the insulation may be of various kinds and inserted according to 65 its characteristics.

If granular or powdered insulation is employed, it is poured into the jacket and compacted therein after the resistor has been inserted.

70 Granular insulation has the advantage that it will very readily flow into the jacket and around and about the resistor.

A machine by which granular or powdered insulation may be poured into the jacket and compacted is herein set forth. 75

After the heater is assembled and the terminals fastened thereto, the jacket is finally ordinarily swaged or otherwise contracted crosswise to further compress and compact the insulation therein and around and about the resistor. The insulation insulates the resistor from the jacket and its turns from each other. It further holds the resistor and its terminal in place so that the heater may be bent into various forms. 80 85

Forms of heater.

The heater is complete in itself and may be employed either alone or applied to heating appliances. 90

It is originally straight in form as shown in Fig. 11 or may be bent into other forms as shown in Figs. 12 to 21 according to the purpose for which it is to be used.

Fig. 12 shows a helical heater, and Fig. 13 95 a reflexed heater which may be used either alone or applied to heating appliance.

Fig. 14 shows an immersion heater which may be suspended within a vessel to heat liquid therein. 100

Fig. 15 shows a looped heater which may be applied to a plate or other body to be heated.

Figs. 16 and 17 show the looped heater fastened to the surface of a plate. 105

Figs. 18 and 19 show the looped heater set in a grooved form in a plate.

Figs. 20 and 21 show the looped heater inclosed within a plate, the plate being either molded over the same or formed in 110 two sections.

Filling machine.

Figs. 22 to 24 illustrate a machine by which the insulation may be inserted and 115 compacted.

The machine comprises in general a vibratory carrier 12 which is provided with an upper bracket 13 and a lower bracket 14 between which the heater is supported. 120

The upper bracket is recessed to receive the end of the jacket and the lower bracket has a yielding seat 15 to receive the heater terminal.

The resistor is held in position by a cord 125 16 attached thereto and connected to a reel 17.

The insulation, powdered or granular, is carried in a can 18 mounted upon the carrier and having its spout located to feed the 130

insulation into the jacket through a hole in the bracket 13.

The carrier is mounted upon a spring 19 and is vibrated by means of a rotary cam 20.

5 A tubular tamper 21 provided with radial lugs 32, extends into the jacket and serves to center and position the resistor and tamp the insulation.

This tamper is lifted and dropped by 10 yielding rotary jaws 23.

When the machine is in operation, the carrier is vibrated up and down and the tamper lifted and dropped and accordingly the insulation is both shaken and tamped to 15 compress the same within the jacket.

Of course various other machines may be provided and other ways adopted to apply the insulation.

What is claimed is:

20 1. An electric heater complete in itself, comprising a winding resistor, insulation compacted and compressed around and about the same, a tubular metal jacket surrounding the insulation and contracted 25 crosswise thereon to compact and compress the same, and a terminal rigidly fastened to the jacket and connected to the resistor.

2. An electric heater complete in itself, comprising an elongated tubular metal 30 jacket, a terminal rigidly fastened to and insulated from the jacket, a winding resistor arranged within the jacket and connected to the terminal, and insulation compacted within the jacket and compressed 35 upon, around and about the resistor.

3. An electric heater complete in itself, comprising an elongated ductile tubular metal jacket, a terminal rigidly fastened to and insulated from the jacket, a winding 40 resistor arranged within the jacket and connected to the terminal, and magnesium oxide compacted within the jacket and compressed upon, around and about the resistor.

45 4. An electric heater complete in itself, comprising an elongated tubular metal jacket, a terminal rigidly fastened to and insulated from the jacket, a winding resistor arranged within the jacket and connected to the terminal, and granular magnesium oxide compacted within the jacket and around and about the resistor.

50 5. A bendable electric heater complete in itself and having in combination an elongated bendable tubular metal jacket, terminals rigidly fastened to the jacket, one at each end thereof, a winding resistor arranged within the jacket and connected to the terminals, and insulation compacted 55 around and about the resistor by crosswise contraction of the jacket.

60 6. An electric heater complete in itself, comprising an elongated tubular metal jacket, a helical resistor arranged therein, terminals rigidly fastened to the jacket and

closing the ends thereof, and insulation compacted within the jacket and around and about the resistor to insulate the resistor from the jacket and hold it in place.

7. An electric heater complete in itself, 70 comprising an elongated tubular metal jacket, a helical resistor arranged therein, terminals rigidly fastened to the jacket and closing the ends thereof, and magnesium oxide compacted within the jacket and 75 around and about the resistor to insulate the resistor from the jacket and hold it in place.

8. An electric heater complete in itself, comprising an elongated tubular metal jacket, a helical resistor arranged therein, 80 terminals rigidly fastened to the jacket and closing the ends thereof, and granular magnesium oxide compacted within the jacket and around and about the resistor to insulate 85 the resistor from the jacket and hold it in place.

9. An electric heater complete in itself, comprising a helical resistor, insulation around and about the resistor, a tubular metal jacket surrounding the insulation and contracted crosswise to compress and compact the insulation, and terminals connected 90 to the resistor and rigidly fastened to the jacket and closing the ends thereof.

10. An electric heater complete in itself, 95 comprising a helical resistor, granular magnesium oxide around and about the resistor, a tubular metal jacket surrounding the insulation and contracted crosswise to compress and compact the insulation, and terminals 100 connected to the resistor and rigidly fastened to the jacket and closing the ends thereof.

11. An electric heater complete in itself, comprising an elongated tubular metal 105 jacket, a winding resistor arranged therein, insulation compacted within the jacket and around and about the resistor, a terminal fastened to the jacket, and a connector having greater conductivity than the resistor 110 and connecting the resistor and the terminal.

12. An electric heater complete in itself, comprising a helical resistor, connectors provided at the ends of the resistor and having greater conductivity than the resistor, insulation around and about the resistor, a tubular jacket surrounding the resistor, and terminals fastened to the jacket and attached to the connector.

13. An electric heater complete in itself comprising a helical resistor, connectors provided at the ends of the resistor and having greater conductivity than the resistor, insulation around and about the resistor, a 125 jacket surrounding the insulation and contracted crosswise thereon to compress and compact the same, and terminals fastened to the jacket and connected to the connectors.

14. An electric heater complete in itself, 130

comprising a helical resistor, connectors provided at the ends of the resistor and having greater conductivity than the resistor, insulation around and about the resistor, a jacket surrounding the insulation and contracted crosswise thereon to compress and compact the same, and terminals rigidly fastened to the jacket closing the ends thereof and having the connectors 10 joined thereto.

15. An electric heater complete in itself comprising an elongated ductile tubular jacket, a helical resistor arranged within the jacket, granular insulation compacted

15 within the jacket and compressed upon the resistor to hold it and its convolutions in place and to insulate the same, the jacket being contracted crosswise to compact the insulation and compress it upon the resistor 20 and insulated terminals rigidly fastened to the jacket, one at each end thereof, and having the resistor connected thereto.

16. A bendable electric heater complete in itself and having in combination an elongated ductile tubular metal jacket, terminals rigidly fastened to the jacket, one at each end thereof and insulated therefrom, a ductile helical resistor arranged within the jacket and connected to the terminals, and 30 granular insulation compacted within the jacket and compressed upon, around and about the resistor by crosswise contraction of the jacket.

17. An electric heater comprising an elongated ductile tubular metal jacket, a ductile helical resistor, arranged therein, insulation compacted within the jacket and compressed upon, around and about the resistor by crosswise contraction of the jacket to hold 40 it in place and insulate it from the jacket and its convolutions from each other.

18. An electric heater comprising an elongated ductile tubular metal jacket, a ductile helical resistor arranged therein, insulation compacted within the jacket and compressed upon the resistor to insulate it from the jacket and its convolutions from each other and hold it in place, and terminals rigidly fastened to said jacket and insulated there- 50 from.

19. An electric heater comprising a winding resistor, insulation compressed upon said resistor, and an elongated tubular jacket surrounding said insulation and contracted crosswise to compact said insulation and compress it upon said resistor.

20. An electric heater comprising a helical resistor, insulation compressed upon said resistor, and an elongated ductile tubular jacket surrounding said insulation and contracted crosswise to compact said insulation and compress it upon said resistor.

21. An electric heater complete in itself comprising a helical resistor, insulation compressed upon said resistor, an elongated tu-

bular jacket surrounding said insulation and contracted crosswise to compact said insulation and compress it upon said resistor, and terminals rigidly fastened to said jacket, one at each end thereof, and insulated there- 70 from.

22. A bendable electric heater complete in itself and having in combination an elongated ductile tubular metal jacket, terminals rigidly fastened to the jacket, one at each 75 end thereof and insulated therefrom, a ductile helical resistor arranged with the jacket and connected to the terminals, and insulation compacted within the jacket and compressed upon, around and about the resistor 80 by crosswise contraction of the jacket.

23. The process of making an electric heater which comprises placing a winding resistor within a tubular metal jacket, filling the space around and about the resistor and 85 between the same and the jacket with insulation, and contracting the jacket crosswise to compact the insulation and compress it upon the resistor, so that the resistor and its convolutions are firmly held in place and the 90 resistor insulated from the jacket and its convolutions from each other.

24. The process of making an electric heater which comprises placing a helical resistor within and in spaced relation to a tubular metal jacket, compacting insulation between the resistor and the jacket, and contracting the jacket crosswise to compact the insulation further and compress it upon, 95 around and about the resistor, so that the 100 resistor and its convolutions are firmly held in place and the resistor insulated from the jacket and its convolutions from each other.

25. The process of making an electric heater which comprises assembling a helical resistor within and in spaced relation to a tubular metal jacket with granular insulation therebetween, and contracting the jacket crosswise to compress and hold the insulation upon the resistor, so that the 105 resistor and its convolutions are firmly held in place and the resistor insulated from the 110 jacket and its convolutions from each other.

26. A process of making an electric heater characterized by positioning a helical resistor within a tubular jacket, inserting insulation within the jacket and packing it around and about the resistor, and contracting the jacket crosswise to compact further the insulation and compress it upon the 120 resistor, so that the resistor and its convolutions are firmly held in place and the resistor insulated from the jacket and its convolutions from each other.

27. A process of making an electric heater 125 characterized by positioning a helical resistor within a tubular jacket, inserting insulation within the jacket and packing it around and about the resistor, and swaging the jacket to contract it crosswise and thus 130

compact the insulation and compress it upon the resistor, so that the resistor and its convolutions are firmly held in place and the resistor insulated from the jacket and its convolutions from each other.

28. A process of making an electric heater characterized by positioning a helical resistor within a tubular jacket, inserting granular insulation within the jacket and 10 packing it around and about the resistor,

and contracting the jacket crosswise to compact further the granular insulation and compress it upon the resistor, so that the resistor and its convolutions are firmly held in place and the resistor insulated from the 15 jacket and its convolutions from each other.

In witness whereof, I have hereunto subscribed my name.

EDWIN N. LIGHTFOOT.

DISCLAIMER.

1,359,400. *Edwin N. Lightfoot, New York, N. Y. ELECTRIC HEATER.* Patent dated November 16, 1920. Disclaimer filed April 25, 1922, by the assignee, *The Cutler-Hammer Mfg. Co.*

Enters its disclaimer—

“To so much of claims 17, 19, and 20 of said patent, and each of them, as may cover an electric heater which is not bendable and not of such length or elongation that the resistor cannot be accurately and effectively centered or spaced with respect to the tubular metal jacket by tension imposed upon the resistor;

“Thereby limiting said claims 17, 19, and 20 of said patent, and each of them, to an electric heater which is bendable and of such length or elongation that the resistor must be centered or spaced mechanically and progressively in advance of and as the filling with the insulation proceeds and independently of the tension imposed on the resistor.

“Your petitioner further enters its disclaimer to so much of claims 23, 24, 25, 26, 27, and 28 of said patent, and each of them, as may cover a process in which the resistor is not placed, assembled or positioned within the tubular metal jacket by positively and mechanically centering or spacing the resistor continuously and progressively in advance of and as the filling with insulation proceeds;

“Thereby limiting said claims 23, 24, 25, 26, 27, and 28, and each of them, to a process of making an electric heater in which the resistor is placed, assembled or positioned within the tubular metal jacket by positively and mechanically centering or spacing the resistor continuously and progressively in advance of and as the filling with insulation proceeds.”

[Official Gazette May 9, 1922.]

1,359,400.—*Edwin N. Lightfoot, New York, N. Y. ELECTRIC HEATER.* Patent dated November 16, 1920. Disclaimer filed October 18, 1923, by the assignee, *The Cutler-Hammer Mfg. Co.*

Hereby enters its disclaimer—

“To so much of claims 1, 2, 3, 4, 5, 15, 16, 18, 21 and 22 of said patent, and each of them, as may cover an electric heater in which the terminal or terminals are not tubular and do not have a portion extending into the end or ends of the tubular metal jacket;

“Thereby limiting said claims 1, 2, 3, 4, 5, 15, 16, 18, 21 and 22 of said patent, and each of them, to an electric heater in which the terminal or terminals are tubular and have a portion extending into the end or ends of the tubular metal jacket;

“To so much of claims 6, 7 and 8, of said patent, and each of them, as may cover an electric heater in which the terminals are not tubular and do not have a portion extending into the ends of the tubular metal jacket and are not secured thereto by the swaging of the jacket;

“Thereby limiting said claims 6, 7 and 8 of said patent, and each of them, to an electric heater in which the terminals are tubular and have a portion extending into the ends of the tubular metal jacket and are secured thereto by the swaging of the jacket;

“To so much of claims 9 and 10 of said patent, and each of them, as may cover an electric heater in which the terminals are not tubular and do not have a portion extending into the ends of the tubular metal jacket and are not secured thereto by the swaging of the jacket and to the resistor by the swaging of the terminals;

“Thereby limiting said claims 9 and 10 of said patent, and each of them, to an electric heater in which the terminals are tubular and have a portion extending into the ends of the tubular metal jacket and are secured thereto by the swaging of the jacket and to the resistor by the swaging of the terminals.”
